(57) **CLAIM**

The ornamental design for a blade assembly for a wind power generator, as shown and described.

DESCRIPTION

FIG. 1 is a perspective view of a blade assembly for a wind power generator.

FIG. 2 is a front elevation view thereof, the right and left side elevation views and rear elevation view being identical thereto.

FIG. 3 is a top plan view thereof; and,

FIG. 4 is a bottom plan view thereof.
